ATTORNEY

UNITED STATES PATENT OFFICE

144,737

DESIGN FOR A STEREOSCOPE

Seton I. Rochwite, Wauwatosa, Wis.

Application July 3, 1945, Serial No. 120,477

Term of patent 14 years

(Cl. D57—1)

To all whom it may concern:

Be it known that I, Seton I. Rochwite, a citizen of the United States, residing at Wauwatosa, in the county of Milwaukee and State of Wisconsin, have invented new, original, and ornamental Design for Stereoscopes, of which the following is a specification, reference being had to the

accompanying drawing, forming a part thereof.

The figure is a perspective view of a stereoscope, showing my new design.

I claim:

The ornamental design for a stereoscope, as shown.

SETON I. ROCHWITE.
